COMBINED LAMP AND SEWING STAND

Robert H. Oakes, Gloucester, Mass.

Application March 14, 1955, Serial No. 35,028

Term of patent 7 years

(Cl. D48—20)

Fig. 1

I claim:

The ornamental design for a combined lamp and sewing stand, as shown.
